(57) **CLAIM**

The ornamental design for a remote controller for industrial robot, as shown and described.

DESCRIPTION

FIG. 1 is a front, top, and left side perspective view of a remote controller for an industrial robot;

FIG. 2 is a front elevation view thereof;

FIG. 3 is a rear elevation view thereof;

FIG. 4 is a top plan view thereof;

FIG. 5 is a bottom plan view thereof; and,

FIG. 6 is a right side elevation view thereof, the left side elevation view being a mirror image thereto.

1 Claim, 6 Drawing Sheets
